(57) **CLAIM**

The ornamental design for a bump bar/keypad shelf bracket, as shown and described.

DESCRIPTION

FIG. 1 is a front side perspective view of a bump bar/keypad shelf bracket of the instant invention.

FIG. 2 is a front elevation view of the bracket of FIG. 1.

FIG. 3 is a rear elevation view of the bracket of FIG. 1.

FIG. 4 is a side elevation view of the bracket of FIG. 1, the opposing side view being a mirror image thereof.

FIG. 5 is a top plan view of the bracket of FIG. 1; and, FIG. 6 is a front side perspective view of the bracket of FIG. 1.

The broken lines showing of a bump bar/keypad are for the purpose of illustrating environment and form no part of the claim.

1 Claim, 6 Drawing Sheets
